CLAIM

The ornamental design for a card applique, as shown and described.

DESCRIPTION

FIG. 1 is a perspective view of the card applique showing our new design.

FIG. 2 is a back view thereof; and,

FIG. 3 is a perspective view thereof; wherein the card applique is applied to a credit card or similar card.

The broken line showing of portions of the card applique is included for the purpose of illustrating environmental structure and forms no part of the claimed design.

The card applique has not appreciable thickness.
